9 Claims. (Cl. 200—88)

This invention relates generally to electric circuit breakers, and more particularly to a thermally and magnetically responsive circuit breaker of the molded case variety suitable for controlling the automatic opening of branch circuits rated as low as five amperes at 240 volts.

Automatic electric circuit breakers of the type disclosed in British Patent No. 893,282, published April 4, 1962, are often installed to protect relatively low voltage and low power circuits, as found, for example, in residential and small commercial buildings, against over-load and fault conditions. Basically, such a circuit breaker comprises a pair of separable contacts, a spring-operated mechanism for effecting separation of the contacts, and a trip device that automatically releases the operating mechanism upon the occurrence of predetermined conditions in the electric circuit in which the circuit breaker is connected.

One form of trip device often utilized in circuit breakers of the general type disclosed in the aforementioned patent comprises a thermally responsive element in the form of an elongated bimetallic strip arranged to carry the current of the circuit to be protected and which, upon continuation of a moderate over-load, heats sufficiently to flex and thereby release the spring-actuated contact-operating mechanism. The trip device also includes a magnetic assembly that becomes operative upon the occurrence of a severe over-load or a fault condition in the circuit to release the operating mechanism more quickly than can the thermally responsive element. Such former circuit breakers have been designed to operate satisfactorily in branch circuits rated at fifteen amperes, 120 volts, but these former circuit breakers will not operate satisfactorily to protect branch circuits rated at five amperes, 240 volts.

Accordingly, the principal object of the present invention is to provide a trip device of increased sensitivity that is rendered operative upon flow of a relatively low over-load or fault current to open the contacts of a circuit breaker.

Circuit breakers are mounted in panelboards which have become standardized in design, and thus the exterior dimensions or configuration of circuit breakers must be such that they can be accepted in the panelboard. Therefore, it is important that any improvement or change in the trip device of a circuit breaker be accomplished without necessitating a change in a critical external dimension or configuration of the circuit breaker.

Because of cost and installation space requirements, the electrical spacing between conductive components of a circuit breaker is already at the acceptable minimum and cannot be materially reduced without reducing the rating of the circuit breaker. Therefore, in order to maintain the critical external dimensions, a trip device operable at lower currents preferably has the same general configuration as the trip device it is to replace and the size is restricted. Further, operation at higher voltages increases the difficulty of extinguishing arcs that occur upon contact separation. In order to maintain the critical exterior dimensions of higher voltage circuit breakers, a rearrangement of circuitry through the circuit breaker

is necessary to provide space for a larger arcing chamber and de-ionizing plates.

Another object of the present invention is to provide a trip device of increased sensitivity and a larger arcing chamber for a circuit breaker of lower current and higher voltage rating without requiring a change in a critical dimension of the circuit breaker, thereby enabling the circuit breaker to be used in the same size electrical panelboard as circuit breakers of lower voltage and higher current rating.

One method of increasing the sensitivity of the fault current response of a trip device comprising a magnetic core and an associated armature, and wherein a magnetic flux is induced in the magnetic core by an electrical conductor, is to increase the effective ampere turns with respect to the core. Since the amount of current is determined by the circuit in which the circuit breaker is used, the effective ampere turns can be increased only by increasing the number of turns of the electrical conductor about the core. Because the exterior dimensions of the trip device cannot be materially increased, the increased number of turns must be accommodated substantially within the confines of the original trip device.

Another object of the present invention is to provide a trip device in which a thermally responsive conductor and a non-thermally responsive conductor are electrically connected in series and are supported in cooperative relation with a magnetic core and with each other to provide a plurality of turns about the core without increasing a critical dimension of the circuit breaker, thereby enabling the circuit breaker to be used in the same size electrical panelboard as circuit breakers of lower voltage and higher current rating.

Another object is to provide an improved trip device comprising a magnetic yoke through which a thermally responsive element in the form of a bimetallic strip extends and wherein the operative flux in the yoke is developed in part by current flowing through the thermally responsive element and in part by current flowing through a conductor wound about one leg of the yoke and electrically in series with the thermally responsive element.

A further object is to provide an improved trip device comprising a thermally responsive bimetal that responds to heat developed by relatively small currents.

Yet another object is to provide an improved magnetic core and armature support which is deformable in accordance with the size of air gap required to provide a circuit breaker having a desired magnetic trip point.

Other objects and advantages of this invention will become apparent from the following description wherein reference is made to the drawings, in which:

FIG. 1 is a view of a circuit breaker constructed in accordance with this invention, the cover having been removed, certain parts being shown in section, and the mechanism being shown in "on" position;

FIG. 2 is a sectional view taken generally along the line 2—2 of FIG. 1 but including the cover;

FIG. 3 is a fragmentary sectional view taken generally along the line 3—3 of FIG. 4 but including the cover;

FIG. 4 is a fragmentary view similar to FIG. 1 but showing the mechanism of the circuit breaker in "tripped" position;

FIG. 5 is a view similar to FIG. 4 but showing the mechanism of the circuit breaker in "off" position;

FIG. 6 is a fragmentary view of the combination magnetic core and armature support and certain associated parts of the circuit breaker of FIG. 1 as viewed from the left in FIG. 1;

FIG. 7 is a fragmentary view similar to the right-hand portion of FIG. 1 but showing a second embodiment of the invention;

FIG. 8 is a sectional view taken generally along the line 8-8 of FIG. 7 but including the cover;

FIG. 9 is a view of the line terminal and certain associated parts of the circuit breaker of FIG. 7 as viewed from the left in FIG. 7;

FIG. 10 is a view similar to FIG. 7 but with certain portions broken away;

FIG. 11 is a view similar to FIG. 10 but illustrating an adjusted air gap between the armature and core of the circuit breaker; and

FIG. 12 is a perspective view of the combination magnetic core and armature support of the circuit breaker.

FIGS. 1-6 show an embodiment of the invention for low current ratings. The molded case of the circuit breaker of FIGS. 1-6 includes a base 20 and a cover 21 molded of insulating material and secured together by a plurality of rivets 22. The base and cover are provided with molded recesses and barriers for supporting the other parts of the circuit breaker, as will be understood.

A load terminal including a shiftable connector body 24 and a clamping screw 25 is provided adjacent one end of the case. The clamping screw bears against one side of an end portion of a terminal strap 26 to move the connector body and clamp a wire (not shown) between the connector body and the other side of the terminal strap.

A stationary contact 28 is secured to the other end portion of the terminal strap 26 for cooperation with a movable contact 30 secured to the bight portion of a generally U-shaped contact arm 32 pivotally supported in a pair of inwardly extending spaced leg portions 33 of an operating handle 34 pivotally supported in the base 20 and cover 21. A hole 35 is provided in the handle 34 for the reception of a handle tie bar (not shown) when it is desired to provide a multiple circuit breaker similar to that shown in British Patent No. 827,740, published February 10, 1960.

A slideable arc shield member 36 formed of insulating material is hooked to the contact arm 32. An over-center tension spring 38 is hooked at one end to the bight portion of the contact arm 32 and at the other end to a generally U-shaped releasably latchable cradle member or trip lever 40 pivotally mounted adjacent one end on a projection 41 of the base 20 between the load terminal 24 and the contact arm 32 and releasably latchable at the other end in a slot 43 of an armature member 44 provided with a reversely bent tail portion 45. The trip lever 40 extends through the handle 34 between the spaced leg portions 33 and carries a reset pin 46 cooperable with the leg portions 33 in the resetting or relatching of the trip lever after it has tripped. A hole 48 is provided in the trip lever for the reception of a pin (not shown) cooperable with a common-trip crossbar (not shown) mountable in the base 20 and cover 21 when knockouts such as the knockout 50 shown in the base 20 are removed to provide a multipole circuit breaker similar to that shown in the aforesaid Patent No. 827,740.

The armature 44 is provided with a thin generally Z-shaped latch plate 52 extending through the slot 43 and having opposite end portions secured to opposite sides of the armature on opposite sides of the slot. The latch plate 52 is shown as being thicker than it is in actual practice due to limitations of drawing.

In accordance with the invention and as best shown in FIG. 12, a combination magnetic core and armature support is provided which includes a relatively large generally U-shaped magnetic core portion 54, a smaller generally U-shaped armature support portion 55, and a connecting portion 56 extending along the inner surface of the base 20 and connecting one leg portion of the magnetic core portion 54 with a corresponding leg portion of the armature support portion 55. A cylindrical projection 58 on the base 20 extends through an opening in the connecting portion 56 and the adjoining leg of the armature support portion 55, and a tongue 59 extends

ing oppositely of the connecting portion 56 from the adjoining leg of the magnetic core portion 54 is anchored or received in a recess in a boss 60 on the base 20 to secure the magnetic core and armature support in position between the base 20 and cover 21. The armature 44 is pivotally supported on the armature support portion 55 and is biased clockwise as viewed in FIGS. 1, 4, and 5 by a helical compression spring 62 seated in a wall portion of the base 20.

10 A line terminal 64 is provided adjacent the other end of the case from the load terminal 24. In the embodiment shown, the line terminal 64 is generally U-shaped as shown in FIG. 6 to provide a pair of plug-in type terminal jaws. A solid wire conductor 66 is secured at one end to the line terminal 64 and is wound several times around the leg portion of the magnetic core portion 54 opposite the connecting portion 56 and around an insulating sleeve 67 thereon and is secured at the other end to one end of a mounting bracket 68 held in position against a pair of rounded raised bearing portions 71 and 73 on an end wall portion of the base 20 by a screw 69. A bimetallic member 70 is secured at one end to the other end of the bracket 68 and extends through the magnetic core portion 54 between the legs thereof. 15 The bracket 68 is resiliently deformable by rotation of the screw 69 to vary the position of the free end of the bimetallic member 70 with respect to the tail portion 45 of the armature 44 and thus calibrate the thermal tripping point of the circuit breaker. A flexible braided wire 20 conductor or cable 72 is secured at one end to the other or free end of the bimetallic member 70 and is secured at the other end to the contact arm 32.

An arc chute assembly including a plurality of deionizing plates 74 held in spaced relationship to each other in a formed insulating fiberboard enclosure 75 is provided for the separable contacts 28 and 30. The base 20 is provided with a pair of vent passages 76 and 77 extending from opposite sides of the arc chute assembly, the passage 77 venting between the jaws of the line terminal 64. A mechanical mounting clip 78 is provided adjacent the other end of the case from the line terminal 64.

25 Movement of the handle 34 from the position shown in FIG. 1 to the position shown in FIG. 5 shifts the pivot point of the contact arm 32 across the axis of the spring 38 and causes the spring to pivot the contact arm to the "off" position, and conversely, movement of the handle back to the position of FIG. 1 causes the spring to pivot the contact arm back to the "on" position.

30 Pivoting the armature 44 counterclockwise as viewed in FIG. 1 unlatches the trip lever 40 and causes the spring 38 to pivot the contact arm 32, handle 34, and trip lever 40 to their "tripped" positions shown in FIG. 4. Movement of the handle 34 toward the "off" position of FIG. 5 causes the leg portions 33 to pivot the reset pin 46 counterclockwise in FIG. 4 about the projection 41 to reset or relatch the trip lever.

35 The unlatching of the trip lever 40 from the latch plate 52 in the slot 43 of the armature 44 may be caused either thermally by engagement of the free end of the bimetallic member 70 with the tail 45 of the armature upon sustained moderate overload current or magnetically by sufficient energization of the magnetic core portion 54 upon a heavy overload such as that caused by a short circuit current.

40 It will be noted that the line terminal 64 and load terminal 24 are reversed with respect to the operating mechanism from their positions as shown in the circuit breaker of the aforesaid Patent No. 893,282, and that a larger arc chute has been provided.

45 The thermal and magnetic tripping unit herein disclosed lends itself very readily to production of circuit breakers of various current ratings. Thus, for the lowest rating, a relatively large number of turns may be provided 50 in the winding of the conductor 66 about the magnetic

core portion 54 to produce sufficient magnetic flux to trip the circuit breaker upon occurrence of relatively low short circuit currents, and the conductor 66 may be made of nickel-chromium or other high resistance wire to produce additional heat for activating the bimetallic member 70 upon relatively low sustained overload currents. For progressively higher ratings, fewer turns may be provided in the conductor 66, and the material thereof may be changed to copper to reduce the heat input to the bimetallic member 70. For still higher ratings, the construction shown in the modification of FIGS. 7-11 may be used.

In FIGS. 7-11, the conductor 66 has been replaced by a formed conductive strap member 80 secured at one end to the line terminal 64 and extending outside of the magnetic core portion 54 to the mounting bracket 68 to which its other end is secured. The strap member 80, bracket 68, and bimetallic member 70 thus provide merely one turn for the magnetic circuit defined by the magnetic core portion 54 and the armature 44. The number of turns cannot be further reduced without eliminating the magnetic flux, but circuit breakers with still higher current ratings may be produced by increasing the air gap as best shown in FIGS. 10 and 11. Thus, the connection between the tongue 59 and its associated leg of the magnetic core portion 54 is weakened by the forming of a recess in one side of the tongue, leaving a relatively narrow connecting portion 82 joining the rest of the tongue to the magnetic core portion. The connecting portion 82 may be laterally bent in one direction before assembly of a circuit breaker to increase the air gap in the assembly and thus produce a circuit breaker with a higher magnetic trip point, or the connecting portion may be bent in an opposite direction to decrease the air gap. In FIG. 10, the armature 44 is shown in the relative position it assumes when latched, and an angle A is shown between the armature and the magnetic core portion 54. In FIG. 11 the angle A has been increased by bending of the connecting portion 82 before assembly of the circuit breaker, thus increasing the air gap and producing a circuit breaker having a higher magnetic trip point.

The distance between the line terminal 64 and the mounting clip 78 has been maintained the same as in the circuit breaker of the aforesaid Patent No. 893,282, and the distance between the handle 34 and the line terminal 64 and mounting clip 78 has also been maintained the same as in the aforesaid patent, although the line terminal and mounting clip have been reversed from their positions in the aforesaid patent relative to the handle. Thus the circuit breaker of this invention and that of the aforesaid patent can be used with the same size panelboard, yet the circuit breaker of this invention has been provided with a larger arc chute so as to be able to handle higher voltages and with a tripping device capable of operating both thermally and magnetically at lower currents than the corresponding currents of the prior device of the aforesaid patent.

Various modifications may be made in the structure shown and described without departing from the spirit and scope of the invention.

This invention is claimed as follows:

1. An electric circuit breaker comprising a molded case, a pair of separable contacts in said case, a releasably latchable trip lever pivotally mounted in said case and releasable from a latched position to effect separation of said contacts, an integral magnetic core and armature support member disposed in said case and including a generally U-shaped magnetic core portion and a generally U-shaped armature support portion, and an armature

pivotaly mounted on said armature support portion and having a free end portion normally spaced from and adapted to be attracted toward said magnetic core portion to effect release of said trip lever, the length of the leg portions of said magnetic core portion measured from the bight portion thereof being at least as great as the length of said bight portion measured between said leg portions and the greater portion of the length of one leg portion of said magnetic core portion being free of direct connection to the corresponding one leg portion of said armature support portion.

2. An electric circuit breaker as claimed in claim 1, wherein said armature support portion and said magnetic core portion are connected solely by a single flat connecting portion.

3. An electric circuit breaker as claimed in claim 1, wherein said armature support portion and said magnetic core portion are connected solely by a connecting portion joining the other leg portion of said magnetic core portion with the corresponding other leg portion of said armature support portion.

4. An electric circuit breaker as claimed in claim 1, wherein the leg portions of said magnetic core portion are longer than the leg portions of said armature support portion.

5. An electric circuit breaker as claimed in claim 1, wherein the bight portions of said magnetic core portion and said armature support portion are offset from each other.

30 6. An electric circuit breaker as claimed in claim 1, wherein said integral magnetic core and armature support member is pivotally connected to said case adjacent said armature support portion and said magnetic core portion is provided with a tongue anchored in said case, 35 said tongue being bendable before installation of said integral magnetic core and armature support member in said case to predetermine the size of the air gap between said armature and said magnetic core portion.

7. An electric circuit breaker as claimed in claim 1, 40 including a line terminal electrically connected to a movable one of said contacts both in an open and in a closed position thereof with respect to a stationary one of said contacts by means including a formed electrically conductive strap member disposed outside said magnetic core portion between said magnetic core portion and a wall of said case.

8. An electric circuit breaker as claimed in claim 1, 45 including a line terminal electrically connected to a movable one of said contacts both in an open and in a closed position thereof with respect to a stationary one of said contacts by means including an electrical conductor wound around said one leg portion of said magnetic core portion.

9. An electric circuit breaker as claimed in claim 1, 55 including a bimetallic member in said case having a free end portion adapted to move said armature toward said magnetic core portion and a line terminal electrically connected to said bimetallic member by means including an electrical conductor formed of relatively high resistance wire and wound a plurality of times around said one leg portion of said magnetic core portion.
